US00D669278S

(12) **United States Design Patent**
Kumazawa

(10) **Patent No.:** **US D669,278 S**
(45) **Date of Patent:** ** *Oct. 23, 2012

(54) **CHAIR**

(75) Inventor: **Taku Kumazawa**, Aichi-ken (JP)

(73) Assignee: **Aichi Co., Ltd.**, Aichi-ken (JP)

(*) Notice: This patent is subject to a terminal disclaimer.

(**) Term: **14 Years**

(21) Appl. No.: **29/365,477**

(22) Filed: **Jul. 9, 2010**
